(57) **CLAIM**

The ornamental design for a polymeric junction box, as shown and described.

DESCRIPTION

FIG. 1 is a perspective view of a first embodiment of a polymeric junction box in accordance with the present design.

FIG. 2 is a front view thereof;

FIG. 3 is a rear view thereof;

FIG. 4 is a top plan view thereof;

FIG. 5 is a bottom plan view thereof;

FIG. 6 is a left side view thereof;

FIG. 7 is a right side view thereof;

FIG. 8 is a perspective view of a second embodiment of a polymeric junction box in accordance with the present design.

FIG. 9 is a front view thereof;

FIG. 10 is a rear view thereof;

FIG. 11 is a top plan view thereof;

FIG. 12 is a bottom plan view thereof;

FIG. 13 is a left side view thereof; and,

FIG. 14 is a right side view thereof.

The broken line showing of knock-outs is for the purpose of illustrating portions of the polymeric junction box and forms no part of the claimed design.
